DISCHARGE APPARATUS FOR FLUIDS AND SEMIFLUID SUBSTANCES

Paul Faulkner Crothers, London, England, assignor to Trier Bros. Limited, London, England, a company of Great Britain

Application August 7, 1939, Serial No. 288,871
In Great Britain August 17, 1938

15 Claims. (Cl. 221—47.1)

This invention relates to discharge apparatus for fluid and semifluid or plastic substances of the kind comprising a cylinder in which is mounted to slide a floating piston which divides the cylinder into two chambers, one of which is adapted to be filled with the substance to be discharged while the other is connected to means, for example a pump, for delivering liquid (hereinafter called pressure liquid) thereto under pressure and at a rate determined in accordance with the desired rate of discharge.

For the sake of convenience the chamber adapted to contain the substance to be discharged will hereinafter be referred to as the upper chamber while that to which the pressure liquid is delivered will be referred to as the lower chamber although the reverse arrangement or arrangements in which the cylinder is horizontal or inclined may be adopted.

The object of the present invention is to provide an improved apparatus of the above kind in which the replenishing of the upper chamber with the substance to be discharged is made possible in a simple and effective manner.

To this end apparatus of the above kind according to the present invention comprises a cylinder containing a floating piston which divides the cylinder into upper and lower chambers, means for connecting the upper chamber to a discharge passage for the substance to be discharged, a pump adapted to be operated by power-driven mechanism for delivering pressure liquid to the lower chamber at a rate determined in accordance with the desired rate of discharge and manually operated mechanism for operating a pump whereby pressure liquid can be withdrawn from the lower chamber at a rate considerably in excess of that at which the power-operated pump is adapted to deliver pressure liquid.

Preferably the manually operated mechanism is such that the withdrawal of pressure liquid from the lower chamber can be effected at a rate many times greater than that at which it is delivered thereto by the power-operated pump to effect discharge of the substance from the upper chamber so that while, as is usually required, discharge is comparatively slow, taking for example a number of hours, the withdrawal of the pressure liquid from the lower chamber when replenishment of the upper chamber is required, can be effected rapidly say in a few minutes or less.

With such an arrangement the power-operated pump may either be stopped or continue to op-

erate during the operation of the manually operated pump.

In any case, the upper chamber in addition to means for connecting it to a discharge passage may be provided with means for connecting it to an inlet passage adapted to communicate with a source of supply of the substance to be discharged so that when the floating piston is moved downwards by withdrawal of pressure liquid from the lower chamber by the manually operated pump, the upper chamber is automatically replenished. In this case the inlet and discharge passages are conveniently provided with non-return valves although manually operated valves may be employed if desired. Alternatively after the piston has been drawn downwards the upper chamber may be adapted to be replenished by hand, for example through a filling opening normally closed by a suitable cap, plug or the like or by removing the upper end of the cylinder.

Preferably a relief valve is provided for permitting escape of pressure liquid delivered by the power-operated pump when the pressure of this liquid exceeds a predetermined value, for example when the floating piston reaches the end of its upward or discharge stroke if the manually operated pump is not immediately actuated to withdraw pressure liquid from the lower chamber.

In addition a pressure gauge subject to the pressure of the pressure liquid delivered by the power-operated pump is preferably provided to indicate when the pressure exceeds the value normally necessary to effect discharge, thus enabling an operator to see when the manually operated pump should be actuated to replenish the cylinder with the substance to be discharged.

Means are conveniently provided for varying the rate of delivery of the power-operated pump so as to vary the rate of discharge. Thus, in one arrangement means may be provided for varying the stroke of the piston of this pump. In this case the means may comprise a shaft mounted to oscillate and carrying a piston-actuating arm or crank for actuating the pump piston, a shaft-actuating arm mounted to rock freely about the axis of the shaft and adapted to be connected to power-operated mechanism, for example by an actuating rod or link, and adjustable stops on the shaft or a member carried thereby for limiting and controlling the extent of free oscillating movement of the actuating arm relatively to the shaft.

Thus, by varying the extent of this free move-

ment, the degree of oscillation imparted to the shaft and hence the stroke of the pump can be varied. In addition, the shaft-actuating arm may be adapted to be connected at any one of a 5 number of points in its length to the actuating rod, link or the like so that the degree of oscillation imparted thereto can be varied.

In addition, or alternatively, the effective rate of delivery of the pump may be varied by providing in the end of the pump cylinder not occupied by the pump piston a dummy piston pressed towards the pump piston by a spring into engagement with a stop which is adjustable to vary the position of rest of the dummy piston, 10 this dummy piston, when in its position of rest, covering a delivery port or ports for liquid. Thus, by adjusting the position of rest of the dummy piston by means of the stop, the extent of movement of this dummy piston under the action of 15 liquid trapped between it and the pump piston before the delivery port opens to permit delivery, and hence the quantity of pressure liquid delivered on each pump piston stroke can be varied.

In such an arrangement the stop may be formed 20 or mounted on a cage which also acts as an abutment for the spring acting on the dummy piston and is adjustable so as to vary the position of rest of the dummy piston without however altering the force exerted thereon by the spring since 25 the dummy piston stop and spring then move as a unit with the cage.

Further a fixed stop limiting the movement of the dummy piston against the action of its spring after it has uncovered the delivery port may be 30 provided so that delivery of pressure liquid will take place irrespective of the pressure in the delivery port.

In any case the pressure liquid delivered by the power-operated pump preferably passes 35 through a sight glass either on the suction or delivery side of the pump so as to enable the rate of delivery and hence the rate of discharge of the substance from the upper chamber to be gauged. Preferably the sight glass is on the suction 40 side of the pump so as not to be exposed to the pressure of delivery.

The invention may be carried into practice in various ways but one construction according to the invention is illustrated in the accompanying 45 drawings, in which

Figure 1 is a side elevation partly in section,

Figure 2 is an end elevation partly in section on the line 2—2 of Figure 1,

Figure 3 is a section on the line 3—3 of Figure 1,

Figure 4 is a section on the line 4—4 of Figure 3,

Figure 5 is a side elevation partly in section showing the upper end of the apparatus with means for replenishing it from a tin or container, and

Figure 6 is a cross-sectional elevation of a sight feed which may be used in the construction illustrated.

In the construction illustrated the apparatus comprises a base A on which is formed a vertical cylinder B containing a floating piston B¹ dividing the cylinder into upper and lower chambers B²B³. The piston as shown is provided with packing of cup leather or other type for preventing flow of fluid past it in either direction.

Closing the upper end of the cylinder B is an 65 end cap C provided with an outlet passage C¹ 70 communicating with a delivery pipe C² and controlled by an automatic non-return valve C³. Also formed in the cap C is an inlet passage C⁴ 75 controlled by an automatic non-return valve C⁵

of the spring-leaf type and adapted to be connected through a pipe C⁶ with a container or reservoir from which a fresh supply of lubricant or other substance (hereinafter termed lubricant) to be delivered by the apparatus can be drawn 5 into the chamber B² when necessary. It will be seen that the valve C⁵ is of a type having a comparatively large area of opening and offering little resistance to inflow from the pipe C⁶.

Also formed on the cap C is a projection C⁷, 10 the lower end of which acts as a stop to limit the upward movement of the piston B¹.

Communicating with the lower chamber B³ is a delivery passage D for pressure liquid, for example oil, to which pressure liquid can be supplied 15 by a power-operated pump comprising a pump casing E secured to the base A and lying within a pressure liquid sump A¹ secured to the base A and adapted to form a source of supply from which the pump draws pressure liquid and 20 delivers it through the delivery passage D. Formed in the pump casing E is a bore E¹ constituting the pump cylinder into one end of which projects a pump piston E² while into its other end projects a dummy piston E³. The pump piston E² is 25 adapted to be reciprocated by a lever F engaging a slot in a member F¹ secured to the end of the pump piston and mounted upon a shaft F² arranged to have oscillating movement imparted thereto by mechanism hereinafter described. 30 The movement of the pump piston E² is such that at or towards the end of each suction stroke it uncovers an inlet port E⁴ in the bore E¹ communicating through a filter E⁵ with the sump A¹, so that during the initial part of the delivery 35 stroke of the piston E² until the piston E² covers the port E⁴, pressure liquid is returned to the sump through the port E⁴.

The dummy piston E³ is pressed towards the pump piston by a spring G and is provided with 40 a collar E⁶ acting as a stop which so limits its movement under the action of the spring G that, when in its position of rest, it covers a delivery port leading to the delivery passage D and controlled by a non-return valve D¹. It will be seen 45 that by varying the position of rest of the dummy piston E³ the quantity of liquid delivered during each stroke of the pump piston E² can be varied. Thus if the dummy piston is adjusted so that in its position of rest it lies nearer to the piston 50 E², the quantity of liquid delivered to the passage D will be reduced and vice versa.

In order to enable the position of rest of the dummy piston to be controlled, the dummy piston extends into a casing G¹ which is capable of 55 sliding but not of rotating within the casing E and contains the spring G acting on the dummy piston. The end of the casing G¹ remote from the dummy piston E³ is closed by a cap G² acting as an abutment for the spring G and having a 60 screwthreaded bore which is engaged by a screwthreaded rod G³ passing through but held from axial movement relatively to a cap G⁴ secured to the casing E. The rod G³ is arranged to be rotated by hand through a detachable connection 65 G⁵ by a knurled adjusting member G⁶. The righthand end of the rod G³ acts as a stop for the dummy piston which limits its movement to the left so that it is held from further movement in this direction when it has uncovered 70 the delivery port leading to the passage D. Thus, whatever the pressure in the passage D the delivery of liquid through the valve D¹ is assured for the whole of the remaining part of the stroke of the piston E² after the dummy piston E³ has 75

uncovered the delivery port and engaged the end of the rod G³. It will also be seen that the construction shown for adjusting the position of rest of the dummy piston enables this adjustment to be effected without altering the effective force of the spring G when the dummy piston is in its position of rest.

Communicating with the delivery passage D is a passage D² leading through a relief valve D³ back into the sump A¹ and also communicating with a pressure gauge D⁴.

Also communicating with the lower chamber B³ is a suction passage H leading to a bore H¹ in the base A constituting the cylinder of a manually operated pump comprising a pump plunger H² pivotally connected at its outer end to a lever H³ which is pivotally connected to one end of a link H⁴, the other end of which is pivoted to the base A. Mounted to slide within the end of the bore H¹ remote from the plunger H² is a dummy piston H⁵ acted upon by a compression spring H⁶ and having a flange H⁷ which acts as a stop such that in its position of rest the piston H⁵ covers an outlet port H⁸ leading from the bore H¹ into the sump A¹. The lever H³ is provided with a socket adapted to receive the end of a handle H⁹, and it will be seen that when the lever H³ is rocked by the handle H⁹ so as to reciprocate the plunger H², the pump will draw operating liquid through the passage H from the lower chamber B³ and discharge it through the outlet passage H⁸. Moreover this hand-operated pump is of such capacity in relation to the power-operated pump that withdrawal of the operating liquid from the lower chamber B³ can be effected rapidly by hand even when the power-operated pump is in continuous operation.

The mechanism whereby the shaft F² is rocked comprises a part K rigidly secured to the shaft F² and having a projecting spigot K¹ on which is mounted to rock freely a plate L spaced from but rigidly secured to a second plate L¹ by two studs L². Also mounted to rock freely upon the spigot K¹ is an arm K² disposed between the plates L and L¹. The plate L¹ is provided with two arcuate slots L³ adapted to receive adjustable stops L⁴ with which the arm K² cooperates. The arm K² is adapted to be connected, for example by a link K³, to suitable power-operated mechanism whereby the arm is oscillated, and it will be seen that by adjusting the stops L⁴ it is possible to vary the degree of free movement of the arm K² between the stops L⁴ and hence the extent of oscillating movement imparted by the arm K² through the stops to the plates L L¹. Normally the plate L is rigidly connected to the part K by a spring-pressed bolt member K⁴ having a handle K⁵ and a pin K⁶ adapted to slide in a slot in the part K so that by moving the bolt K⁴ against the action of its spring by means of the handle K⁵ and then turning this handle through a small angle, the pin K⁶ will hold the bolt in its withdrawn position so that the part K is disconnected from the plate L. In this way rocking movement of the part K and hence of the shaft F² with the plate L can be prevented if desired, while moreover the arrangement enables the shaft F² to be rocked by hand, for example through a socket K⁷ secured to the end remote from the part K when desired. For this purpose the handle H⁹ may be arranged to fit the socket member K⁷.

It will be appreciated that the part K may be secured to the shaft F² in any desired rotational position according to the position desired for the arm K².

The part K may be provided with lugs K⁸ cooperating with stops K⁹ on the casing A appropriately disposed to limit the maximum rocking movement of the part K for the purpose of avoiding excessive reciprocation being imparted to the piston E².

An oil level gauge M is conveniently secured to the sump A¹ so as to indicate the oil level therein, and alternative positions for this oil gauge may be provided on the sump. Further, a cap M¹ normally closing a filling aperture in the casing A is provided to enable the oil in the sump to be replenished when desired. It will be appreciated that the oil level in the sump at any moment will give an indication of the quantity of oil in the chamber B³ and hence of the quantity of lubricant still in the chamber B².

The arm K² may be provided with alternative holes for the pivot connecting the link F³ thereto so as to enable the oscillation of this arm to be varied or a suitable point of connection chosen in accordance with the movement of the power-driven member to which the link K³ is coupled.

In operation it will be seen that the oscillation of the arm K² acts through the stops L⁴, the plates L¹ and L and the part K to oscillate the shaft F² and hence to cause reciprocation of the piston E². The piston E² thus draws operating liquid from the sump A¹ and delivers it through the delivery passage D to the lower chamber B³ at a rate determined by the settings of the stops L⁴ and of the dummy piston E³. The liquid thus delivered forces the piston B¹ upwards to discharge lubricant at the desired rate through the passage C¹ and pipe C². When the piston B¹ reaches the end of its upstroke, so that further pressure liquid cannot be delivered to the chamber B³, the gauge D⁴ will show a rise in pressure and liquid delivered by the piston E² will flow through the relief valve D³ back into the sump. The upper chamber B² can then be replenished by manual operation of the plunger H² through the lever H³ by the handle H⁹ so as to withdraw operating liquid from the chamber B³ and thus cause the piston B¹ to descend and draw in a fresh charge of lubricant through the passage C⁴.

Figure 5 shows an arrangement whereby the upper chamber B² can be replenished with semi-solids such as grease from a portable container in the form of a tin, of the known kind in which a piston constituted by a metal disc with a hole in its centre forming the discharge aperture rests upon the surface of the lubricant in the tin adjacent to its lid and is adapted to be pressed downwards to cause discharge of lubricant through the hole. Thus in this arrangement the passage C⁴ has secured thereto an adapter N having a head N¹, the aperture in which is surrounded by a flexible packing ring N². Normally closing the aperture in the head N¹ is a cap O having a handle O¹ rigidly secured to a short shaft O² projecting therefrom. Freely surrounding the shaft O² is a collar O³ having radially projecting arms O⁴ to each of which is connected one end of a tension spring O⁵, the other end of which is connected to the adapter at O⁶. When the chamber B² is to be replenished, the cap O is withdrawn from the head N¹ against the action of the springs O⁵ and a tin container P of the kind referred to above containing a plate-like piston P¹ with a central hole P² is applied to the head N¹ as shown so that the plate P¹ rests upon the packing N² with the cap O resting upon the base of the container P. It will be seen that when pressure liquid is now withdrawn by the plunger H² from

the chamber B^3 so that the piston B^1 descends, lubricant is forced from within the tin P through the aperture P^2 , the adapter N and the passage C^4 into the chamber B^2 . Conveniently the capacity of the chamber B^2 is such in relation to that of the tin P that the tin P will thus be completely emptied so that it can then be removed and the cap O again applied to the head N^1 .

Where a liquid lubricant is to be delivered by the apparatus it will be understood that the chamber B^2 may be replenished by pouring such lubricant through a filling aperture normally closed by a removable plug indicated at C^8 .

In some cases the piston E^2 instead of drawing pressure liquid direct from the sump A^1 may draw it through a sight glass so as to enable the rate of delivery of pressure liquid to be observed. In this case the sight glass may be constructed, for example, as shown in Figure 6. In this construction the sight glass comprises a tubular body Q containing a glass tube Q^1 which can be viewed through a slot or slots Q^2 . The upper end of the tubular body is closed by a cap Q^4 between which and the lower end of the body the glass tube Q^1 is gripped so that with the assistance of packing rings Q^5 the ends of the glass tube make fluid-tight joints with these parts. The lower end of the body is formed with an outlet passage Q^6 while the cap Q^4 carries an inlet passage Q^7 with a wire R extending between the inlet and outlet passages to guide oil flowing from one to the other. The inlet passage Q^7 leads out of a chamber S closed at its upper end by a valve housing S^1 in which is mounted a valve S^2 acted upon by a spring S^3 and having a hollow stem the bore of which communicates at one end with an inlet chamber S^4 and at its other end with radial ports S^5 in the stem.

The arrangement is such that when no suction is applied to the outlet passage Q^6 the valve occupies the position shown so that the ports S^5 are closed but when sufficient suction is applied to the outlet passage Q^6 , the valve moves downwards so as to open the ports S^5 to admit oil to the chamber S which then flows through the passage Q^7 and the glass tube Q^1 along the wire R into the outlet passage Q^6 .

In a modification of the construction shown in Figures 1 to 4 of the drawings, the piston E^2 may be operated by a rotating shaft through a cam or eccentric engaging a slot in a member connected to the piston. It is to be understood, however, that the invention is not limited to any particular way of operating the power-operated pump or the manually operated pump.

What I claim as my invention and desire to secure by Letters Patent is:

1. Delivery apparatus of the piston and cylinder type for liquid and semiliquid substances including in combination a cylinder, a floating piston in the cylinder dividing it into a delivery substance chamber and an operating liquid chamber, a discharge passage communicating with the delivery substance chamber, a first pump arranged to be operated by power-driven mechanism for delivering operating liquid to the operating liquid chamber at a rate determined in accordance with the desired rate of discharge, a second pump for withdrawing operating liquid from the operating liquid chamber at a rate considerably in excess of that at which the first pump is adapted to deliver operating liquid, and means whereby the said second pump can be actuated manually.

2. Delivery apparatus of the piston and cylin-

der type for liquid or semiliquid substances including in combination a cylinder, a floating piston in the cylinder dividing it into a delivery substance chamber and an operating liquid chamber, a delivery passage and an inlet passage communicating with the delivery substance chamber, valves for controlling the delivery and inlet passages, a first pump arranged to be operated by power-driven mechanism for delivering operating liquid to the operating liquid chamber at a rate determined in accordance with the desired rate of discharge, a second pump for withdrawing operating liquid from the operating liquid chamber at a rate considerably in excess of that at which the first pump is adapted to deliver operating liquid, and means whereby the said second pump can be actuated manually.

3. Delivery apparatus of the piston and cylinder type for liquid and semiliquid substances including in combination a cylinder, a floating piston in the cylinder dividing it into a delivery substance chamber and an operating liquid chamber, delivery and inlet passages communicating with the delivery substance chamber, automatic non-return valves controlling the delivery and inlet passages, a first pump arranged to be operated by power-driven mechanism for delivering operating liquid to the operating liquid chamber at a rate determined in accordance with the desired rate of discharge, a second pump for withdrawing operating liquid from the operating liquid chamber at a rate considerably in excess of that at which the first pump is adapted to deliver operating liquid, and means whereby the said second pump can be actuated manually.

4. Delivery apparatus of the piston and cylinder type for liquid and semiliquid substances including in combination a cylinder, a floating piston in the cylinder dividing it into a delivery substance chamber and an operating liquid chamber, a discharge passage communicating with the delivery substance chamber, a first pump arranged to be operated by power-driven mechanism for delivering operating liquid to the operating liquid chamber at a rate determined in accordance with the desired rate of discharge, a second pump for withdrawing operating liquid from the operating liquid chamber at a rate considerably in excess of that at which the first pump is adapted to deliver operating liquid, and means whereby the said second pump can be actuated manually, and a relief valve permitting escape of operating liquid delivered by the first pump when the pressure in the operating liquid chamber exceeds a predetermined value.

5. Delivery apparatus of the piston and cylinder type for liquid and semiliquid substances including in combination a cylinder, a floating piston in the cylinder dividing it into a delivery substance chamber and an operating liquid chamber, delivery and inlet passages communicating with the delivery substance chamber, automatic non-return valves controlling the delivery and inlet passages, a first pump arranged to be operated by power-driven mechanism for delivering operating liquid to the operating liquid chamber at a rate determined in accordance with the desired rate of discharge, a second pump for withdrawing operating liquid from the operating liquid chamber at a rate considerably in excess of that at which the first pump is adapted to deliver operating liquid, means whereby the said second pump can be actuated manually, and a relief valve permitting escape of operating liquid delivered by the first pump when the pressure in

- the operating liquid chamber exceeds a predetermined value.
6. Delivery apparatus of the piston and cylinder type for liquid and semiliquid substances including in combination a cylinder, a floating piston in the cylinder dividing it into a delivery substance chamber and an operating liquid chamber, a discharge passage communicating with the delivery substance chamber, a first pump arranged to be operated by power-driven mechanism for delivering operating liquid to the operating liquid chamber at a rate determined in accordance with the desired rate of discharge, a second pump for withdrawing operating liquid from the operating liquid chamber at a rate considerably in excess of that at which the first pump is adapted to deliver operating liquid, means whereby the said second pump can be actuated manually, and a pressure gauge for indicating the pressure in the operating liquid chamber.
7. Delivery apparatus of the piston and cylinder type for liquid and semiliquid substances including in combination a cylinder, a floating piston in the cylinder dividing it into a delivery substance chamber and an operating liquid chamber, a discharge passage communicating with the delivery substance chamber, a first pump arranged to be operated by power-driven mechanism for delivering operating liquid to the operating liquid chamber at a rate determined in accordance with the desired rate of discharge, a second pump for withdrawing operating liquid from the operating liquid chamber at a rate considerably in excess of that at which the first pump is adapted to deliver operating liquid, means whereby the said second pump can be actuated manually, a relief valve permitting escape of operating liquid delivered by the first pump when the pressure in the operating liquid chamber exceeds a predetermined value, and a pressure gauge for indicating the pressure in the operating liquid chamber.
8. Delivery apparatus of the piston and cylinder type for liquid and semiliquid substances including in combination a cylinder, a floating piston in the cylinder dividing it into a delivery substance chamber and an operating liquid chamber, a discharge passage communicating with the delivery substance chamber, a first pump arranged to be operated by power-driven mechanism for delivering operating liquid to the operating liquid chamber at a rate determined in accordance with the desired rate of discharge, a second pump for withdrawing operating liquid from the operating liquid chamber at a rate considerably in excess of that at which the first pump is adapted to deliver operating liquid, means whereby the said second pump can be actuated manually, and means for varying the rate of delivery of the first pump.
9. Delivery apparatus of the piston and cylinder type for liquid and semiliquid substances including in combination a cylinder, a floating piston in the cylinder dividing it into a delivery substance chamber and an operating liquid chamber, delivery and inlet passages communicating with the delivery substance chamber, automatic non-return valves controlling the delivery and inlet passages, a first pump arranged to be operated by power-driven mechanism for delivering operating liquid to the operating liquid chamber at a rate determined in accordance with the desired rate of discharge, a second pump for withdrawing operating liquid from the operating liquid chamber at a rate considerably in excess of that at which the first pump is adapted to deliver op-
- erating liquid, means whereby the said second pump can be actuated manually, and means for varying the rate of delivery of the first pump.
10. Delivery apparatus of the piston and cylinder type for liquid and semiliquid substances including in combination a cylinder, a floating piston in the cylinder dividing it into a delivery substance chamber and an operating liquid chamber, a discharge passage communicating with the delivery substance chamber, a first pump arranged to be operated by power-driven mechanism for delivering operating liquid to the operating liquid chamber at a rate determined in accordance with the desired rate of discharge, a second pump for withdrawing operating liquid from the operating liquid chamber at a rate considerably in excess of that at which the first pump is adapted to deliver operating liquid, means whereby the said second pump can be actuated manually, and means for varying the rate of delivery of the first pump, such means comprising a shaft mounted to oscillate, an arm on the shaft actuating the pump piston, a shaft-actuating arm mounted to rock freely about the axis of the shaft and adapted to be connected to power-operated mechanism, a member connected to the shaft, and adjustable stops on the said member for limiting and controlling the extent of free movement of the shaft-actuating arm relatively to the shaft.
11. Delivery apparatus of the piston and cylinder type for liquid and semiliquid substances including in combination a cylinder, a floating piston in the cylinder dividing it into a delivery substance chamber and an operating liquid chamber, a discharge passage communicating with the delivery substance chamber, a first pump arranged to be operated by power-driven mechanism for delivering operating liquid to the operating liquid chamber at a rate determined in accordance with the desired rate of discharge, a second pump for withdrawing operating liquid from the operating liquid chamber at a rate considerably in excess of that at which the first pump is adapted to deliver operating liquid, means whereby the said second pump can be actuated manually, and means for varying the rate of delivery of the power-operated pump, such means comprising a spring-pressed dummy piston in the end of the pump cylinder remote from the pump piston, a stop limiting the movement of the dummy piston under the action of its spring so that in its position of rest it covers a delivery port in the pump cylinder, means for adjusting the position of the stop so as to vary the position of rest of the dummy piston, and a fixed stop which permits movement of the dummy piston against the action of its spring until it uncovers the delivery port but prevents further movement of the dummy piston against the action of its spring.
12. Delivery apparatus including in combination the elements set forth in claim 10, in which means are provided whereby the member carrying the stops can be coupled to and uncoupled from the oscillating shaft at will.
13. Delivery apparatus including in combination the elements set forth in claim 11, in which the member acting as the adjustable stop for the dummy piston is rigid with the member acting as the abutment for the spring acting on the dummy piston whereby the effective force of this spring when the dummy piston is in its position of rest is unaffected by movements of the adjustable stop.
14. Delivery apparatus including in combination the elements set forth in claim 10, in which the shaft-actuating arm is adapted to be con-

nected by a link to power-operated mechanism for oscillating it and is formed so that the point in its length at which the link is connected thereto can be varied.

5 15. Delivery apparatus including in combination the elements set forth in claim 2, wherein there is combined with the inlet passage a tubular adapter, a packing ring surrounding the aperture at the free end of the adapter, a cap normally

closing the free end of the adapter, one or more tension springs for holding the cap in place and such that the cap can be withdrawn against the action of the tension springs and a container for lubricant then applied to the adapter between the free end of the adapter and the cap so that the adapter enters the end of the container and the cap bears upon the base of the container.

PAUL FAULKNER CROTHERS.
